UNITED STATES PATENT OFFICE.

ALBERT HUGH STEVENSON, OF LONDON, ENGLAND.

PAPER, CARDBOARD, AND LIKE RECEPTACLE OR CONTAINER.

Application filed August 2, 1921. Serial No. 489,330.

To all whom it may concern:

Be it known that I, ALBERT HUGH STEVENSON, a subject of the King of Great Britain, residing in London, England, have invented 5 certain new and useful Improvements in and Relating to Paper, Cardboard, and like Receptacles or Containers, of which the following is a specification.

This invention relates to receptacles or 10 containers of the kind comprising a body portion of paper, cardboard, or like material having a metal bottom and a metal protecting or securing rim round the open mouth thereof.

15 The object of the invention is to produce a receptacle of this kind in a more economical manner than heretofore.

According to the invention, the body of 20 the receptacle is tapered, or so formed that its mouth is wider than the bottom and the proportions between the diameters of the mouth and the bottom are so arranged that the metal bottom and the metal rim for the mouth may be formed from a single metal 25 sheet or disc, the sheet or disc being of such a size that it may be stamped out into a central circular portion, forming the bottom of the container and a concentric annulus forming the rim thereof. These stamped 30 out portions do not require any forming or shaping other than the usual rolling or bending in applying them to the receptacle. Preferably, the disc is stamped from a metal sheet and divided into the bottom and rim 35 forming portions in a single operation, but obviously the stamping may be carried out in a series of separate operations if desired. The metal bottom and the rim so formed 40 may be applied to the body portion by any of the known pressing and rolling methods usually employed.

To enable the invention to be fully understood it will now be described by reference to the accompanying drawing in which the 45 application of the invention to a conical tubular container is illustrated:

Fig. 1 is an elevation of a conical tubular container with a metal bottom and rim formed according to the invention.

50 Fig. 2 is a plan view of a metal disc from which the metal bottom and rim portions are formed and

Fig. 3 is a plan view of the disc after the stamping operation, showing the separated 55 portions which form the rim and bottom.

Fig. 4 is a sectional view on line 4—4, Fig. 3, through the rim forming portion of the stamped blank and

Fig. 5 is a similar view through the bottom forming portion of the stamped blank. 60

As shown, the container comprises a tapered body portion 1 of any suitable paper-like material such as paper, cardboard, fiber board, etc., having a metal rim 2 and a metal bottom 3. The proportions between the 65 mouth and bottom of the container 1 are so arranged that the metal portions for forming the metal rim and bottom may be obtained from a disc of metal 4 preferably without any waste. 70

The disc 4 is of such a size that when stamped as illustrated in Fig. 3, the central disc portion 5 forms the bottom of the container and the outer concentric annulus 6 remaining forms the rim. The portions 6 75 and 5 are preferably of the cross sections illustrated in Figs. 4 and 5 respectively.

The bottom portion 5 is attached to the bottom of the container 1 by inserting the dished portion 7 into the open bottom of 80 the container and rolling or bending the flange 8 over the outside edge of the container in the known manner.

Similarly, the rim portion 6 is applied to 85 the container by inserting the vertical portion 9 into the top of the container and rolling or bending the flange portion 10 over the outside edge of the container in the known manner, the completed container having the appearance shown in Fig. 1. 90

Any suitable stamping apparatus and series of stamping operations may be used for forming the disc and the rim and bottom stampings and obviously these stampings may be of shapes other than those illustrated 95 according to the type of rim and bottom it is desired to fit to the container. For example, the bottom need not be dished and the rim may be formed to receive a metal or other lid. 100

Again, while it is preferable to use a blank of such a size that there is no waste of material, the invention may be carried out with a blank in which, after stamping out the desired portions, a ring of surplus material remains. 105

Further, the invention is applicable to containers of shapes other than conical or tapered, for example, the body of the container may be of spherical or curved shape 110

with top and bottom openings so proportioned as to allow the rim and bottom to be formed according to the invention.

Having thus described the nature of the 5 said invention and the best means I know of carrying the same into practical effect, I claim:

1. A container comprising in combination 10 a body portion of paper-like material, a metal rim and a metal bottom, the mouth of the body being wider than the bottom, the proportions between the diameters of the rim and bottom being such that the metal bottom and the metal rim for the mouth can 15 be stamped in two concentric portions from a metal blank.

2. A method of forming the metal rim and 20 metal bottom of a container having a paper-like body, consisting in stamping a metal disc into two concentric circular portions of such a size that the inner circle or disc forms the bottom without any further shaping other than securing it, and the outer concentric annulus forms the rim for the container 25 mouth without any further shaping other than securing it.

3. A container comprising in combination,

a body portion of paper-like material, a metal rim for one end, and a metal bottom for the other end, the metal rim and bottom 30 being formed by stamping two concentric circular portions from a metal blank.

4. A container comprising in combination 35 a frusto-conical body portion of paper-like material, and a metal rim and a metal bottom stamped in two concentric portions from a single blank, the diameters of the ends of the body portion being so chosen that the rim fits one end and the bottom fits the other end. 40

5. The method of forming a container which consists in stamping a metal disk into 45 two concentric portions one adapted to form a rim and the other adapted to form a bottom, and forming a body portion of paper-like material whose ends are of different diameter, the proportion between the diameters being such that the bottom fits one end and the rim fits the other end of the body, and securing the rim and bottom to the ends of 50 the body portion.

In testimony whereof I have signed my name to this specification.

ALBERT HUGH STEVENSON.
